UNITED STATES PATENT OFFICE.

CHARLES E. WALDECK, OF PATERSON, NEW JERSEY.

DESIGN FOR A ROTARY-FAN APPLIANCE.

SPECIFICATION forming part of Design No. 19,259, dated August 6, 1889.

Application filed May 21, 1889. Serial No. 311,622. Term of patent 14 years.

To all whom it may concern:

Be it known that I, CHARLES E. WALDECK, a citizen of the United States, residing at Paterson, county of Passaic, and State of New Jersey, have invented and produced a new and original Design for Rotary Fans, of which the following is a specification, reference being had to the accompanying drawing, forming part thereof.

10 My invention relates to a design for a rotary-fan appliance; and the characteristic feature thereof consists in a shaft having disposed thereon an enlargement of a bulbous or spherical form provided with annular 15 grooves, as seen in the accompanying drawing, wherein the fan is shown in elevation.

In the said drawing, 1 represents the stand for the fan, and 2 is a rotary tubular fan-shaft

having a bulbous or spherical enlargement 3, formed with one or more circumferential 20 belt-grooves 4, and having the gradually-swelled portion 5 near the outer end thereof, wherein the fan-blades 6 are mounted.

Having thus described my design, what I claim as my invention, and desire to secure 25 by Letters Patent, is—

The design for a rotary-fan appliance, substantially as herein shown and described.

In testimony whereof I have hereunto set my hand and affixed my seal, in the presence 30 of the two subscribing witnesses, this 11th day of May, 1889.

CHARLES E. WALDECK. [L. s.]
